UNITED STATES PATENT OFFICE.

FRANK DITCHFIELD, OF MONTREAL, QUEBEC, CANADA.

BOLSTER.

1,143,615.

Specification of Letters Patent. Patented June 22, 1915.

Application filed April 10, 1914. Serial No. 830,931.

To all whom it may concern:

Be it known that I, FRANK DITCHFIELD, a citizen of the Dominion of Canada, and resident of the city of Montreal, in the Province 5 of Quebec and Dominion of Canada, have invented certain new and useful Improvements in Bolsters, of which the following is a full, clear, and exact description.

This invention relates to improvements 10 in bolsters, and the object is to provide a simple, economical and easy method of making bolsters.

A further object is to provide a bolster of decreased cost and increased durability.

15 A still further object is to provide a novel and improved means of connecting the compression and tension members of a bolster.

Another object is to provide means for 20 transmitting the pull of the tension member to the entire end of the compression member, whereby unequal stresses and tearing of the compression member are eliminated.

The most common form of bolster in use 25 at the present time, generally known as the simplex bolster, consists essentially of a compression member of channel section, and a tension member of ordinary rectangular section, connected at its ends to the ends of the compression member and spaced away there- 30 from at the center by a strut. For obvious reasons, it is necessary to bend the web of the compression member, so that its web occupies a plane parallel with the tension member. The end of the tension member is bent 35 over the end of the compression member web and riveted, a suitable filling plate being inserted to increase the radius of bend and to stiffen the end of the compression member web. If this plate becomes broken, there is 40 a strong tendency for the tension member to tear the web of the compression member down between the flanges thereof. Such a bolster is, moreover, fundamentally wrong, in that the pull of the tension member is 45 delivered on only a part of the end of the compression member. In addition to the foregoing defects, the compression member is more or less expensive to make, owing to the necessity of bending the ends into a 50 plane parallel with the tension member.

The present invention aims to overcome 55 these disadvantages by providing a special form of end casting which serves the purpose of the ordinary end casting, and in addition forms a seat against which the entire end of the compression member bears.

This casting is formed to replace the filler and bent portion of the compression member end, so that the compression member is shortened, the operation of bending and the making and inserting of the filler eliminated. The end casting forms the connection between the tension and compression members, and is by reason thereof more securely connected to the bolster than the ordinary end 60 castings. A key is also provided securely holding the compression and tension members in their proper positions relative to one another and to the casting.

In the drawings which illustrate the invention:—Figure 1 is a partial elevation of a bolster formed according to the present invention. Fig. 2 is an enlarged vertical longitudinal section at the center of the bolster end. Fig. 3 is an inner end elevation 75 of the bolster end. Fig. 4 is an outer end elevation of the bolster end.

It will be understood that in the drawings, only the most simple form of end casting is shown, namely, the open bottom type 80 adapted for the insertion of a wood block to form the spring seat. The bottom and sides of this casting may, however, be formed in any suitable way, according to the design of the truck or other structure to which the 85 bolster is applied.

Referring more particularly to the drawings, 5 designates the compression member of ordinary channel section, and 6 the tension member of ordinary rectangular or 90 other section, usually in the form of a strap or narrow plate as shown. These two members are spaced apart at their centers by a strut 7. In the ordinary form of simplex bolster, the ends of the compression member would be bent up to bring the web into a plane parallel with the tension member, and the end of the tension member bent over the end of the compression member web. The end casting would then be riveted to 100 the flanges of the compression member. Moreover, the end casting would be subject to more or less movement relatively to the bolster. The greatest disadvantage, however, is that the pull of the tension member 105 would be exerted only on the web of the compression member, so that the flanges thereof would scarcely be in compression at all and internal stresses be set up in the compression member.

In the present invention the end casting, designated as a whole by the numeral 8,

consists essentially of a top plate 9 overlying the web of the compression member, and side plates 10 embracing the flanges of the compression member. At the point 5 where the converging compression and tension members meet, the compression member is cut off and abuts a rib 11 formed on the top and side plates of the casting. Beyond this rib, that is to say, beyond the end of 10 the compression member, the top plate of the casting is turned upwardly as at 12, in a plane parallel with the tension member. The outer edge of this top plate is thickened, as shown at 13, to replace the ordinary filler. 15 The tension member passes along in contact with the underside of the top plate portion 12 and is bent over the thickened portion 13, and secured in place by rivets 14.

In order to secure the tension and compression members very firmly in their relative positions, a key 15, wedge-shaped in the longitudinal section of the bolster, is inserted between the underside of the compression member web and the upper side of 20 the tension member, and secured in place by rivets 16 and 17 passing through the web and flanges of the compression member and top and side plates of the end casting.

It will be readily seen from the drawing, 30 particularly Fig. 2, that the end casting forms the connection between the compression and tension members and is an integral part of the bolster. The top plate of the casting replaces the bent up end of the compression member, and the filler, and forms the necessary anchorage for the tension member. This top plate is suitably supported and stiffened by the side plates 10, and is as a matter of fact merely in 35 compression between the tension member and the end of the compression member. The seat rib 11, which engages the entire end of the compression member transmits the pull of the tension member to the end 40 tire section of the compression member, so that internal stresses are not set up, the full strength of the compression member is utilized, and no tearing of the web can result. The key member 15 forced in between the tension and compression members 45 prevents the dropping of the compression member, and relieves the top plate of much stress, any tendency to movement being transmitted to and resisted by the tension member. This key member in addition holds the compression member 50 against buckling at the point where it is weakened by the rivet holes.

In the process of manufacture, time and 60 material are saved and a superior bolster produced. The end casting is slipped on to the end of the compression member and the

tension member bent over the thickened lip 13. The bending and subsequent shrinking of the tension member draws the rib 11 very 65 tightly against the end of the compression member, so that a firm connection is made between the parts. After the tension member has been riveted in place, the key member 15 is inserted and driven tightly between the compression and tension members and riveted in position. It will readily be seen that a saving of material is effected by shortening the compression member, and that the operation of bending the end is 70 also eliminated, together with the filler, and the operation of inserting same.

While the end members of the bolster have been referred to as castings, owing to the general practice of using castings at this 80 point, it is obvious that these end members may be stampings or forgings if desired.

Having thus described my invention, what I claim is:—

1. In a bolster, compression and tension 85 members, an end member connecting said compression and tension members at their ends, and a key inserted between the compression and tension members within said end member and connected through the compression member with the end member.

2. In a bolster, compression and tension members, an end member connecting and embracing the ends of said compression and tension members, and a key inserted between 95 the ends of said compression and tension members within and attached to the end member, arranged to hold the compression and tension members against movement relative to one another and to the end member. 100

3. In a bolster, compression and tension members, an end member embracing the top and sides of the compression and tension members, and a key inserted between the 105 ends of the compression and tension members arranged to force the compression member upwardly against the end member.

4. In a bolster, a compression member of channel section and a tension member passing between the flanges thereof, an end member of channel form embracing the extremities of said compression and tension members, an internal rib on said end member forming an abutment for the compression member, and a key inserted between the ends 110 of the compression and tension members arranged to hold the compression member in engagement with its abutment. 115

In witness whereof, I have hereunto set my hand in the presence of two witnesses. 120

FRANK DITCHFIELD.
